UNITED STATES PATENT OFFICE.

JOHN B. MARCO, OF COLLINSVILLE, ILLINOIS.

SAFETY HOOK FOR CARBIDE LAMPS.

Application filed April 18, 1922. Serial No. 554,743.

To all whom it may concern:

Be it known that JOHN B. MARCO, a citizen of the United States, residing at Collinsville, in the county of Madison and State of Illinois, has invented certain new and useful Improvements in Safety Hooks for Carbide Lamps, of which the following is a specification.

This invention relates to miners' carbide lamps, and has particular reference to means used in securing the lamp to a miner's cap, so as to hold same in a firm position and prevent dislodgment of the lamp from the cap as is often the case when a minor stoops over.

A further object of my invention is to provide an attachment for miners' lamps, which will permit a quick and easy adjustment of the lamp to a plate or holder which is usually attached to the top and peak of a miner's cap.

A still further object of this invention is to provide a device of the above stated character, which is simple in construction, efficient for the purpose intended and one that can be manufactured and placed on the market without adding materially to the expense of the lamp itself.

These and like objects of my invention will be better understood as the description proceeds and as is specifically pointed out in the appended claim.

Referring to the accompanying drawing which forms a part of this specification and which clearly illustrates the construction and operation of my improved safety hook attachment,

Figure 1 is a side elevation of a miner's lamp attached to a miner's cap, with my improved hook, parts of the lamp and cap being broken away.

Figure 2 is a side elevation of a miner's lamp showing my improved safety hook attached thereto.

Figure 3 is a perspective view of my improved plate and safety hook holder attached to a miner's cap.

Figure 4 is a transverse section through the plate holder and the safety hook, and

Figure 5 is perspective view of a slightly modified form of safety hook.

Referring to the drawing in detail, like numerals will be used to designate like parts in the different views.

The numeral 1 designates a miner's cap provided with a peak 2 of the usual con-

struction. Attached to the top of the cap as at 3 by any suitable means and to the peak of the cap as at 4, is a metal plate 5. A second metal plate 6 is attached to the front 60 of the metal plate 5 adjacent the point 7 where the plate 5 bends at right angle to the body of same to provide means for securing same to the top of the cap. The plate 6 is secured to the plate 5 by means of rivets 8. 65 The plate 6 is formed intermediate the edges of same and the entire height to provide a pocket 9 between the inner face of the plate 6 and the outer face of the plate 5, as is clearly indicated in cross section in Fig. 4. 70

A hook 10, formed of a single piece of wire is attached to the rear of a miner's lamp designated by the numeral 11. The wire 10 is bent as at 12 to form arms 13, which are connected as at 14. The arms 12 75 are compressed when inserted in the pocket 9 and after same are released they have a tendency to move apart which causes them to firmly engage the walls of the pocket, which will make the lamp 4 more secure to 80 the cap and will not permit same to fall to one side or swing sideways when the wearer's head is tilted or turned. The lamp being held securely to the cap.

In Fig. 5, I have shown a slightly modified form of hook, wherein a spring clip 15 is attached to the lamp in place of the wire hook 10.

The spring clip 15 having a large bearing in the cap opening or pocket which will also 90 act to hold the lamp more secure to the cap and prevent the lamp from falling to one side or swinging sideways when the wearer's head is tilted or turned.

In view of the foregoing description of 95 my invention taken in connection with the accompanying drawing, it is thought that further explanation as to the operation, construction and objects of same are unnecessary.

While I have shown and described the preferred form of my invention, I realize that various minor changes may be resorted to, without departing from the spirit and scope of the invention as claimed, therefore, 105 I do not wish to limit myself to the exact details of construction shown, nor to the combination and arrangement of parts.

What I claim as new and desire to secure by Letters Patent is:—

In combination with a miner's cap and a lamp; a relatively wide plate having its ends

bent angularly in opposite directions coincident to the angle of the top of the crown and the visor of said cap, means securing said ends respectively to the top and visor 5 of said cap to position the body of said plate in a materially spaced relation to the crown of the cap, a second plate having a central transverse channel impressed therein, the side walls of said channel being parallel, 10 means securing said second plate to the outer face of the first mentioned plate so that the upper edge of the former is flush with the upper edge of the first plate proper at its

junction with the upper angularly bent end and the side edges of the second mentioned plate flush with the side edges of the first mentioned plate, the channel in the second mentioned plate forming a vertical pocket and bearing plate for supporting and carrying a substantially U-shaped spring wire 20 hook carried by said lamp, said wire hook adapted to be sprung into secure engagement with the aforesaid pocket. 15

In testimony whereof I affix my signature.

JOHN B. MARCO.
